UNITED STATES PATENT OFFICE.

ALBERT S. CROCKETT, OF NEW YORK, N. Y.

DESIGN FOR A COMMUNICATION-BOARD.

55,593.

Specification for Design.

Patented July 6, 1920.

Application filed September 27, 1919. Serial No. 326,995. Term of patent 7 years.

To all whom it may concern:

Be it known that I, ALBERT S. CROCKETT, a citizen of the United States, residing at New York, in the county of New York and State of New York, post-office address No. 103 Park avenue, in the said city, have invented a new, original, and ornamental Design for Communication-Boards, of which the following is a specification, reference be-

ing had to the accompanying drawing, forming part thereof.

The figure is a plan view of a communication board, showing my new design.

I claim:

The ornamental design for a communication board, as shown.

ALBERT S. CROCKETT.
